UNITED STATES PATENT OFFICE.

EDWARD J. BRANDT, OF WATERTOWN, WISCONSIN, ASSIGNEE TO BRANDT CASHIER COMPANY, OF CHICAGO, ILLINOIS.

AUTOMATIC CASHIER.

1,143,167.

Specification of Letters Patent. Patented June 15, 1915.

Application filed September 20, 1913. Serial No. 790,915.

To all whom it may concern:

Be it known that I, EDWARD J. BRANDT, a citizen of the United States, and resident of Watertown, in the county of Jefferson and State of Wisconsin, have invented certain new and useful Improvements in Automatic Cashiers; and I do hereby declare that the following is a full, clear, and exact description thereof.

10 My invention relates to coin handling machines of the character familiarly known in the art as the "Brandt" type automatic cashier, and as illustrated for example in my prior Patents Nos. 1068307 and 1068308, 15 dated July 22, 1913.

The primary objects of the present invention are to simplify prior constructions of this type, reduce the cost of production, eliminate friction, with the resultant ease in 20 operation, while at the same time to preserve the advantages and efficiency of similar prior constructions.

The various improvements and novel details in the construction and arrangement 25 of parts will be particularly set forth in the description to follow, which for a clear understanding of the invention, should be considered in connection with the accompanying drawings, wherein is disclosed, for illustrative purposes, a convenient and satisfactory embodiment of the invention.

In the drawings:—Figure 1 is a vertical longitudinal sectional view of one embodiment of my invention; Fig. 2 is a transverse 35 sectional view of the machine taken generally on the line 2—2 of Fig. 1; Figs. 3 and 4 are similar views of fragments of the machine, taken respectively on the line 3—3 and 4—4 of Fig. 1; Fig. 5 is a plan view of 40 a fragment of the machine illustrating an arbitrary arrangement of push keys associated with a push bar; and Fig. 6 is a side elevation of a coin tray of the machine detached.

45 Referring more particularly, by numerals, to the drawings, 11 is a casing for the machine and 12 rockers having cranked ends thereof journaled in a frame 13 secured within said casing, the construction and arrangement of said rockers being such as has been heretofore customary in "Brandt"

automatic cashiers. The rockers oppose spring-controlled keys of the machine and like in Letters-Patent above noted, each key preferably includes a vertically reciprocative plate 14 having a foot or feet; each in contact with some one of the rockers, a spring-controlled shank 14' guided in plates 15, 16, of another frame secured in the casing, and a push-button 17 having a rod 17' thereof in connection with the spring held shank 14', the union of said shanks being similar to what was originally disclosed in Letters Patent No. 824,841, of July 3, 1906. The rockers are inclined, and the keys are 55 disposed at right angles to said rockers. The machine herein specified has two rows of push-buttons and an intermediate push-bar 18 provided with stems 19 guided in the frame-plate 15 astraddle of the spring-controlled shanks 21' of a pair of pusher-plates 21*, each having a single foot thereof in contact with a rocker 12' common to both. A rear recessed lug 22 of each plate-shank 21' engages an equalizer bail 23 supported 60 from the brackets 24 projecting from the underside of the frame plate 15. The bail is substantially U-shaped, as shown, the round body portion thereof loosely engaging adjacent the ends thereof in the recesses of the 65 lugs 22, and the offset side arms being pivoted to the brackets, as shown.

Each of the rockers 12 is provided with a bracket 25 pivotally connected to one end of a stiff wire link 26 attached at its other 70 end to a rear extension of a hanger 27, and all the hangers are pivotally suspended from a single rod 28 for oscillatory movement. A spiral-spring 29 connects the rear extension of each hanger 27 with an angle-bar 13' 75 of the frame 13. A similar spring 30 connects each hanger with a coin-pusher 31 pivoted at its inner end to a depending arm 27' of each hanger, this arm being in one piece with the balance of said hanger or a 80 separate piece spaced apart therefrom according as the spacing of the coin-pusher may require. As originally disclosed in Letters Patent No. 1,068,307, aforesaid and herein best shown in Fig. 3, the coin-pusher 85 pivot is preferably a pin provided with a flanged head engaged by one end of a spring-

plate that is fastened at its other end to the adjacent hanger-arm.

From the foregoing it will be understood that the suspension of each coin-pusher is such as to encounter the least frictional resistance in operation, its only point of frictional contact being against the coin-tray 32 of the machine, as shown in Fig. 1. The coin-tray is generally similar to those disclosed in Letters Patent No. 1,068,308 and 1,068,307 aforesaid, and it constitutes an inclined detachable portion of the machine forward of a front plate 11' of the casing, this plate and said tray being provided with bottom grooves in which the coin-pushers reciprocate.

The sides of the casing 11 are provided with inner ribs 33, and the coin-tray is provided with matching-grooves for said ribs by which it is held in working position on a supporting ledge 34 of said casing. The grooved sides of the coin-tray are also serrated at 35, to facilitate grasp of the same when placing said tray in working position or removing it therefrom. A side of the coin-tray is also provided with an upper play-space for a spring-controlled pivotal latch 36 that projects under a top-piece 11" of the machine-casing, as shown in Fig. 1, to prevent lifting away of said tray until the latch is retracted, the upper end of said latch being provided with a projection 36' to facilitate its retraction by thumb-pressure on the part of the operator.

The upper rear flange 32' of the coin-tray is extended at its corners to provide lugs 32" that constitute legs for said tray when the same is removed from the machine and rested upon a convenient support. When the coin-tray is positioned in the machine, its flange and lugs thereof aforesaid are seated in depressions of the top-piece 11" of the machine-casing flush therewith.

The machine is provided with the usual coin-chute 37 into which the lower end of the coin-tray extends and said tray of the machine has compartments for cent, five-cent, dime, quarter dollar and half dollar coins, or coins of any suitable denomination, as desired, the organization of the machine being such that the depression of a key thereof will result in the payment of one dollar or a fractional part of the same, and an operation of the push-bar results preferably in the payment of a five-cent coin, though it is understood, of course, that this is largely dependent on the particular use to which the machine is put. The various keys are indexed for payment of coins singly or in combination to the amount of one cent to one dollar. The keys in the upper row are indexed for amounts greater than one cent and excepting one of the two indexed 25 are operated to pay what is termed "split change", while those in the

lower row are operated to effect a payment of a five or ten cent coin or a combination of coins that go to make up various multiples of ten cents. By a manipulation of any key and the push-bar 18 a payment of 70 five cents more than the value in cents indexed on said key will result, said push-bar being easy of operation and serving to facilitate the payment in sums between two and ten cents, as well as five cents over ten 75 cents or any multiple of the same within the capacity of the machine.

It will be observed that the hangers 27 are pivoted at a point above the rocker bars 12, and the offset extensions of the hangers project rearwardly above the rocker bars 12, to the end that the machine is of less height and width than prior similar machines, and the machine, as a whole, rendered more compact, while at the same time the coin ejecting mechanism is positive and efficient in operation. It will also be appreciated that by reason of the utilization of the spring members 29, connected to the pivoted hangers, as illustrated, which said hangers are in turn connected to the rocker bars, the said spring members 29 accomplish the function of restoring the rocker bars 12 into normal position, as well as the coin ejecting mechanism, *per se*. This arrangement does away with the independent spring members connected to the rocker bars, and thereby further simplifies the construction.

I claim:

1. In an automatic cashier, the combination of rockers and their actuating keys, pivotally supported hangers, a link pivoted at one end to a rocker, and at its opposite end to a hanger, a coin pusher pivotally connected to each hanger, a spring connected at one end to the hanger and at its opposite end to the pusher, intermediate its ends, and a spring connected to each hanger, said last mentioned spring acting to retain said hanger as well as the connected rocker in normal position.

2. In an automatic cashier, the combination of rocker bars having offset terminals loosely mounted for rotary movement in suitable supports, hanger arms pivotally supported adjacent their upper ends at a point overlying the rocker bars, pusher bars pivotally connected to said hanger arms, and upwardly extending rearwardly inclined links interposed between the hanger arms and rockers, said links being pivotally connected at the upper end to the hanger arms intermediate their ends and the lower end to said rocker bars adjacent one terminal thereof.

3. In a device of the character described, the combination of rocker bars, having offset loosely mounted terminals, hangers, one for each rocker bar, said hangers being pivotally supported at their upper ends,

pusher arms connected with the hangers, a link connected between the hangers and rocker bars, key actuated means for rocking the rocker bars in one direction to impart movement to the connected hangers and pusher arms, and springs connected to the hangers for returning both the hangers and rocker bars to normal position.

4. In an automatic cashier, the combination of rocker bars having offset terminals loosely mounted for rotary movement in suitable supports, hanger arms pivotally supported adjacent their upper ends, pusher bars pivotally connected to said hanger arms, links interposed between the hanger arms and rockers, said links being pivotally connected to the hanger arms intermediate their ends and to said rocker bars adjacent one terminal thereof, spiral springs projecting between the hanger arms and pusher bars and connected to each intermediate their ends, said hanger arms having a laterally projecting part intermediate their ends, and an upwardly projecting spring connected at one end to said laterally projecting part and at its upper end to a fixed support.

5. In an automatic cashier, the combination of a rocker, a pair of key-plates having vertically aligned offset feet opposing the rocker, a push-bar common to and connected with shanks of said plates convenient to the operator of the machine for simultaneously operating said feet, and coin-pusher mechanism in connection with the rocker, said pusher bar extending substantially from side to side of the key-board.

6. In an automatic cashier, the combination of a rocker, a pair of key-plates opposing the rocker, a push-bar in connection with shanks of said plates convenient to the operator of the machine, coin-pusher mechanism in connection with the rocker, and a suitably suspended equalizer bail having direct connection with the shanks of said plates intermediate its ends and having offset pivoted terminals.

7. In an automatic cashier, the combination of a rocker, a pair of key-plates opposing the rocker and each having a shank provided with a lug, a push-bar in connection with the plate-shanks, a suitably suspended equalizer bail in engagement with the plate-shank lugs, and coin-pusher mechanism in connection with said rocker.

8. In an automatic cashier, the combination of a casing, a coin tray having detachable vertical sliding connection with the casing, and an upwardly projecting spring latch on the tray to engage under an overhanging portion of said casing, and normally preventing vertical sliding movement of the tray relative to the casing.

9. In an automatic cashier, the combination of a casing, a coin-tray having serrated

sides, and means for securing the tray in detachable connection with the casing, said tray having vertically extending grooves, and the sides of the casing having interengaging ribs whereby the tray may be bodily removed by an upward sliding movement, and means at the top of the casing for normally holding the tray against upward sliding movement.

10. In an automatic cashier, the combination of a casing, a detachable coin-tray provided with lugs adapted to overlie the top of the casing and engageable with the casing and which constitute legs for the tray when detached, and means for securing the tray in connection with said casing.

11. In an automatic cashier, the combination of a horizontally extending supporting rod, a series of depending hanger arms pivotally supported from said rod, an offset extension on said arms, a spring projecting upwardly from said offset extensions, and connected to a fixed part of the machine, links projecting downwardly from said extensions, a series of rockers below the rocker arms having pivotal connection one with each link, means for actuating the rockers, and coin pushers operatively connected with the hanger arms.

12. In an automatic cashier, the combination of a horizontally extending supporting rod, a series of depending hanger arms pivotally supported from said rod, an offset extension on said arms, a spring projecting upwardly from said offset extensions, and connected to a fixed part of the machine, links projecting downwardly from said extensions, a series of rockers below the hanger arms having pivotal connection one with each link, means for actuating the rockers, and coin pushers one for each hanger arm pivotally connected thereto.

13. In an automatic cashier, the combination of a horizontally extending supporting rod, a series of depending hanger arms pivotally supported from said rod, an offset extension on said arms, a spring projecting upwardly from said offset extension, and connected to a fixed part of the machine, links projecting downwardly from said extensions, a series of rockers below the hanger arms having pivotal connection one with each link, means for actuating the rockers, coin pushers one for each hanger arm pivotally connected thereto, and a spring interposed between each coin pusher and its connected hanger arm.

14. In an automatic cashier, the combination of a horizontally extending supporting rod, a series of depending hanger arms pivotally supported from said rod, an offset extension on said arms, springs projecting upwardly from said offset extensions, and connected to a fixed part of the machine, links projecting downwardly from said ex-

tensions, a series of rockers below the hanger arms having pivotal connection one with each link, means for actuating the rockers, a downward projection on the hanger arms, 5 and coin pushers operatively connected to said downward projections.

15. In an automatic cashier, the combination of a horizontally extending supporting rod, a series of depending hanger arms pivotally supported from said rod, an offset extension on said arms, springs projecting upwardly from said offset extensions and connected to a fixed part of the machine, links projecting downwardly from said extensions, a series of rockers below the hanger arms having pivotal connection one with each link, means for actuating the hanger arms, a downward projection on each hanger arm, a coin pusher for each hanger arm, a 10 pivotal connection between the rear end of the coin pushers and said downward projections, and springs projecting downwardly from the hanger arms and connected to the pushers intermediate the ends of the latter.

25. 16. In an automatic cashier, a hanger arm pivoted at its upper end and having a part projecting rearwardly at substantially right angles thereto, a rocker bar below the hanger, key actuating means for the rocker bar, a link pivotally connected at its upper end to said rearward projection of the hanger, and at its opposite end to said rocker bar, and a coin pusher operatively connected to said hanger.

35. 17. In an automatic cashier, a hanger arm pivoted at its upper end and having a part projecting rearwardly at substantially right angles thereto intermediate its ends, a rocker bar below the hanger, key actuating means 40 for the rocker bar, a link pivotally connected at its upper end to said rearward projection of the hanger, a coin pusher pivotally connected to the lower end of the hanger, and a spring connected to said rearward 45 extension of the hanger.

18. In an automatic cashier, a hanger arm pivoted at its upper end and having a part projecting rearwardly at substantially right angles thereto intermediate its ends, a rocker bar below the hanger, key actuating means 50 for the rocker bar, a link pivotally connected at its upper end to said rear projection of the hanger, a coin pusher pivotally connected to the lower end of the hanger, a 55 spring connected to said rearward extension of the hanger, and a spring interposed between the pusher arm and hanger intermediate the ends of the latter.

19. In an automatic cashier, the combination 60 of a key board, a series of keys, an elongated pusher bar extending longitudinally of the machine adjacent the keys, rockers operatively associated with the keys and pusher bar, an elongated equalizing bail extending longitudinally of the pusher bar,

said equalizing bail having at its ends offset parts mounted for rotary movement and having intermediate its ends a pivotal connection with the pusher bar at a point above the rockers.

20. In an automatic cashier, the combination of a key board, a series of keys, an elongated pusher bar extending longitudinally of the machine adjacent the keys, rockers operatively associated with the keys and 75 pusher bar, an elongated pivoted equalizing bail, the body portion of the equalizing bail extending longitudinally of the pusher bar and the side arms of the bail being pivotally connected at their free ends to the frame, 80 and recessed parts on the pusher bar engaging over the body portion of the bail adjacent the opposite ends thereof.

21. In an automatic cashier, the combination of a longitudinally extending series 85 of keys, rockers therefor, a longitudinally extending pusher bar extending substantially from end to end of the series of keys, downwardly projecting pusher plates adjacent opposite ends of the pusher bar, said 90 plates having overlying feet, a rocker adapted to be actuated by both feet and equalizing means for said pusher bar having a pivotal connection therewith adjacent opposite ends thereof.

22. In an automatic cashier, the combination of a longitudinally extending series of keys, rockers therefor, a longitudinally extending pusher bar extending substantially from end to end of the series of keys, downwardly projecting pusher plates adjacent opposite ends of the pusher bar, said 100 plates having overlying feet, a rocker adapted to be actuated by both feet, and an equalizing bail interposed between the pusher bar and 105 rockers.

23. In an automatic cashier, the combination of a casing, a coin tray having vertically extending grooves, vertically extending tongues on the inner sides of the casing to engage said grooves, releasable holding means for preventing slidable movement of the casing and the sides of the tray above said tongues being serrated, substantially as and for the purpose described.

24. In an automatic cashier, the combination of a casing, two longitudinally extending series of keys projecting without the casing, coin pushers, rockers operatively associated with the coin pushers and keys, an 120 elongated longitudinally extending push bar arranged between and substantially co-extensive with the series of keys, a coin pusher and rocker operatively associated with the pusher bar, and an equalizing bail operatively connected with the opposite ends of the pusher bar, said bail including a substantially U-shaped member, the offset arms of which are pivotally mounted to a fixed part at the top of the casing, and a pivotal 125 130

connection between the elongated arm of said U-shaped member adjacent opposite ends thereof, and the pusher bar.

25. In a device of the character described, the combination of a rocker bar, a hanger arm pivoted at its upper end at a point above the rocker bar and having a part projecting rearwardly therefrom, and overlying the rocker bar, key actuated means for the rocker bar, a link pivotally connected at its upper end to said rearward projection of the hanger, and at its opposite end to the rocker bar, said hanger arm and link being confined within the space above the rocker arms whereby to offer substantially no projection beyond the ends thereof, and a coin pusher operatively connected to said hanger.

26. In a device of the character described, the combination of a frame, rocker bars extending transversely of the frame, hangers, one for each rocker bar, said hangers being pivotally supported at a point rearwardly of and above the forward end of said rocker bars, diagonally extending links pivoted at one end to the rocker bars at a point rearwardly of their forward support, and at the other end to the hangers intermediate their ends, and pusher arms operatively connected with said hangers.

27. In a device of the character described, the combination of rocker arms, coin pushers operatively connected therewith, actuating members for the pushers, two rows of keys, a pusher bar extending substantially parallel with and between said rows of keys, said keys being operatively connected with said actuating members, and the pusher bar being operatively connected with one of said actuating members, and the pusher bar being substantially coextensive with both rows of keys whereby the pusher bar may be simultaneously actuated with any individual key throughout either row of keys by one or both hands of the manipulator.

28. In a device of the character described, the combination with a frame, of a series of rocker bars arranged adjacent the base of the frame, a series of pivotally supported hangers having rearwardly extending offset parts overlying the rocker bars, pushers supported by the hangers, and links connecting the offset parts with the pusher bars intermediate the ends of the latter, said hangers and links being positioned in the space above the rocker bars.

29. In a device of the character described, the combination of a series of depending hanger arms, pivotally supported adjacent their upper ends, an offset extension intermediate the ends of said arms, links projecting downwardly from said extensions at a forward inclination, a series of rockers below the rocker arms having pivotal connection one with each link, the offset extension of which latter overlies the rockers,

means for actuating the rockers, coin pushers operatively connected with the hanger arms, and springs connected to said offset extensions of the hanger arms for normally returning said parts to normal position. 70

30. In a device of the character described, the combination of rocker bars, having offset loosely mounted terminals, hangers, one for each rocker bar, said hangers being pivotally supported at their upper ends, pusher 75 arms connected with the hangers, a connection between the hangers and rocker bars, means for rocking the rocker bars in one direction to impart movement to the connected hangers and pusher arms, and springs connected to the hangers for returning both the hangers and rocker bars to normal position.

31. In a device of the character described, the combination of rocker bars having offset loosely mounted terminals, hangers, one for each rocker bar, said hangers having a pivotal support at their upper ends, pusher arms connected to the lower ends of the hangers, connection between said hangers at 85 a point intermediate their ends, and said rocker bars, and springs connected to said hangers intermediate their ends and to a fixed part of the framework of the machine at a point above the hangers. 90

32. In a device of the character described, the combination of rocker bars having offset loosely mounted terminals, hangers, one for each rocker bar, an elongated supporting shaft disposed at a point above the 100 rocker bars, said shaft being common to all of the hangers, and said hangers having a loose sleeved engagement at their upper ends with said shaft, pusher arms connected to the lower end of the hangers, a member 105 connected at one end to the hangers intermediate the ends of the latter and at the opposite end to the rocker bars intermediate the ends of the latter, and springs connected to said hangers intermediate their 110 ends and to a fixed part of the framework of the machine at a point above the hangers.

33. In a device of the character described, the combination of rocker bars having offset loosely mounted terminals, hangers, one 115 for each rocker bar, said hangers being disposed substantially vertically and pivotally supported at their upper ends, pusher arms connected to the hangers at the lower end of the latter, said hangers having a rearwardly extending offset part intermediate their ends, springs connected at one end to the offset part of the hangers and at the opposite end to a fixed part of the framework, and a movable connection between 120 said offset parts of the hangers and the rockers.

34. In a device of the kind described, the combination of substantially horizontally disposed rocker arms, having a body part 130

and offset loosely mounted terminals, hangers, one for each rocker arm, said hangers being pivotally supported at their upper ends at a point above the body part of the 5 rocker arms, and projecting downwardly at a slight inclination toward one of said terminals of the rocker arm, said hangers having intermediate their ends a projection overlying the rocker arms, a link connection 10 between said projections and the body part of the rocker arms, said hangers and associated parts being substantially confined

within the space above said rocker arms whereby to offer substantially no projection therebeyond, and pusher arms operatively 15 connected with said hangers.

In testimony that I claim the foregoing I have hereunto set my hand at Milwaukee in the county of Milwaukee and State of Wisconsin in the presence of two witnesses.
